Patented May 22, 1923.

1,455,876

UNITED STATES PATENT OFFICE.

LEON GRAUMAN, OF DENVER, COLORADO.

LID BRACE.

Application filed April 5, 1922. Serial No. 549,827.

To all whom it may concern:

Be it known that I, LEON GRAUMAN, a citizen of the United States, residing at Denver, in the county of Denver and State 5 of Colorado, have invented certain new and useful Improvements in Lid Braces, of which the following is a specification.

This invention relates to braces for the support of lids or covers of receptacles in an 10 open position, and its primary object is to provide an adjustable device of very simple construction which when fastened at a side of a receptacle, is capable of supporting the lid thereof in a substantially upright position.

When used in connection with the cooling chamber or ice cream cabinet of a soda fountain, my invention provides a ready means to maintain the removable lid in an open position, upon the edge of the rear wall thereof, and thereby eliminates the troublesome and unsanitary practice of removing the lid entirely from its receptacle and placing it on a counter, floor or other temporary support.

Additional advantages of the use of my improved brace reside in that the weight of the open cover aids in holding the brace in its adjusted position, in that the lid in the 30 open position, prevents dirt or articles on the counter of a soda fountain, from falling into the ice cream cabinet and screens the contents of the receptacle from persons seated in front of the counter, and in that the 35 application of the invention does not require its attachment to the cover which is necessary, may be removed from the receptacle as before.

An embodiment of my invention has been 40 illustrated in the accompanying drawings in the several views of which like parts are correspondingly designated and in which—

Figure 1 represents a vertical section 45 through the cooling chamber of a soda fountain showing my invention in its operative position with relation to the open lid thereof;

Figure 2, a transverse section taken on the line 2—2, Figure 1;

Figure 3, an enlarged view of the brace in 50 its retracted position, looking toward the side thereof which in practice faces the side of the box to which it is attached;

Figure 4, a similar view of the brace in 55 its operative position looking toward the outer side thereof;

Figure 5, an edge view of the parts illustrated in Figure 4;

Figure 6, a cross-section taken on the line 60 6—6, Figure 4; and

Figure 7, a fragmentary elevation of the lower portion of the lid and the therewith 65 engaging upper part of the movable member of the brace, drawn to a larger scale.

Referring more specifically to the drawings, the reference numeral 2 designates the cooling chamber of a soda fountain and 3 the removable lid or cover which normally closes the open top thereof.

The brace which holds the lid in the open 70 position shown in Figures 1 and 2, in accordance with the present invention, comprises a longitudinally channeled open-ended keeper 4 which by means of laterally projecting, apertured lugs 5 is in practice, 75 fastened to a side wall of the receptacle.

The channel has in one of its longitudinal edges, an upwardly tapering recess 6 the ends of which extend at substantially right angles to said edge to provide shoulders 7 80 and 8 for the engagement of a correspondingly formed part of the adjustable member of the device, as will hereinafter be described.

The keeper is attached at a side of the receptacle adjacent the rear wall thereof, in a forwardly slanting position and with the recessed edge of its channel uppermost as indicated in Figure 2.

The open upper end of the keeper is 90 slightly below the upper edge of the side wall to which it is fastened, so that in practice, the adjustable member of the device may be extended beyond said edge to engage 95 with the open lid or cover, as shown in the drawings.

The lugs 15 at the side of the keeper adjoining the side wall of the chamber, are dissimilar in length in order to determine the proper slant of the attachment by engagement with said wall, as shown in Figure 2 of the drawings.

The movable member hereinbefore referred to, consists of a bar 9 which in length corresponds with the keeper and which is 105 slidably fitted in the channel of the same.

The bar has in its edge adjoining the recessed edge of the channel, an elongated notch 10 which tapers from its upper end inwardly to a distance from its opposite end 110 which corresponds with the length of the recess.

The end of the notch is at an angle to the edge of the bar, in correspondence with that of the shoulder 8 at the upper end of the recess, and the bar is thus provided with a 5 narrow elongated foot 12 which may enter into the recess by lateral movement of the member when it is in its extended position as shown in Figures 4 and 5.

The bar has at its upper end a head 13 10 which is adapted to engage the lid in the open position without marring the surface thereof, and which when the bar is retracted inside the keeper, tightly closes the upper end of the same to prevent of brine or other 15 liquid entering the channel and interfering with the operation of the device.

It is desirable that the lid in its open position should be substantially vertical and that at the same time it bears upon the upper 20 end of the bar so as to lock it in its extended position by maintaining the foot 12 in the recess of the keeper.

With this object in view, I provide the lid with a beveled abutment piece 14 which engages the head of the bar as best shown in 25 Figure 7 of the drawings, in a plane corresponding with the slant of the bar.

It will be seen that after the lid is placed in the open position by moving it about its 30 rearward edge, the member 9 if partially withdrawn from its keeper, will naturally fall into its locked position when the foot 12 at its lower end, comes in register with the recess 6.

35 The lid engaging with the head of the member as hereinbefore described, holds the member by its weight, against accidental displacement and the lid is thus securely held in the open position until the movable member of the brace is returned to its original position in which the head at its upper end, rests on top of the keeper.

40 It will be apparent that only long and heavy lids require the use of braces at opposite ends of the receptacle to hold it in the open position as shown in Figure 1, and that ordinarily a single brace at one end of the chamber is sufficient.

Having thus described my improved lid-brace, I desire it understood that modifications in the construction and arrangement of the parts thereof may be availed of within the spirit of my invention as defined in the hereunto appended claims.

55 What I claim and desire to secure by Letters Patent is:

1. A brace of the character described, comprising a channeled keeper open at its upper end, and a bar longitudinally slid able therein, the channel of the keeper having a recess in one of its edges, and the bar having at its corresponding edge, a foot adapted to enter said recess when the bar extends partially outside of the keeper through the opening at the upper end thereof.

2. A brace of the character described, comprising a channeled keeper open at its upper end, and a bar longitudinally slid able therein, the bar having in one of its edges, a notch slanting inwardly from its upper end and forming a foot at its opposite end, and the channel of the keeper having in its corresponding edge, a recess adapted to receive said foot when the bar extends partially outside of the keeper through the opening at the upper end thereof.

3. A brace of the character described, comprising a channeled keeper open at its upper end, and a bar longitudinally slid able therein, the bar having in one of its edges, a notch slanting inwardly from its upper end and forming a foot at its opposite end, and the channel of the keeper having in its corresponding edge, a tapering recess adapted to receive said foot when the bar extends partially outside of the keeper through the opening at the upper end thereof.

4. A brace of the character described, comprising a channeled keeper open at its upper end, and a headed bar longitudinally slid able therein, the bar having in one of its edges, a notch slanting inwardly from its upper end and forming a foot at its opposite end, and the channel of the keeper having in its corresponding edge, a recess adapted to receive said foot when the bar extends partially outside of the keeper through the opening at the upper end thereof.

5. The combination with a receptacle having a movable lid or cover, of a brace to support the lid in an open position, comprising a member free from the lid and adjustable to a position in which it lies against the lower portion of the lid in the open position, and means co-operative with the lower portion of said member to lock it in its adjusted position.

6. The combination with a receptacle having a movable lid or cover, of a brace to support the lid in an open position, comprising a member free from the lid and adjustable to a position in which it lies against the lower portion of the lid in a slanting position, and means co-operative with the lower portion of said member to hold it in its adjusted position by the weight of the lid.

7. The combination with a receptacle having a movable lid or cover, of a bar free from the lid and adjustable on the receptacle to partially extend through the opening thereof, against the lower portion of the lid in an open position, and means on the receptacle co-operating with the lower portion of the bar, to hold it in its adjusted position.

8. The combination with a receptacle having a movable lid or cover, of a bar free from the lid and adjustable on the receptacle to partially extend through the opening thereof, against the lower portion of the lid.

in a slanting position, and means on the receptacle co-operating with the lower portion of the bar, to lock it in its adjusted position by the weight of the lid.

5 9. A brace of the character described comprising a channeled keeper open at its upper end, and a bar longitudinally slid able therein, the keeper and the bar having co-operating means to hold the latter in a pre-
10 determined partially withdrawn position, and the bar having a head adapted to close the upper end of the keeper in its retracted position.

10. A brace of the character described comprising a channeled keeper open at its upper end and having at one side laterally projecting lugs of dissimilar length to determine its slanting position by engagement with the wall of a receptacle in which
15 it is fastened, and a bar longitudinally slid able in the keeper, said keeper and said bar having co-operating means to hold the latter in a predetermined partially withdrawn position.

11. In apparatus of the character described, the combination of a receptacle, a movable lid therefor, having a beveled abutment surface, and a brace comprising a slanting member movable to a position in which it engages the abutment surface of
20 the lid when the lid is in the open position, and means cooperating with the member to lock it in its adjusted position by the weight of the lid.

12. In apparatus of the character described, the combination of a receptacle, a movable lid therefor, having a beveled abutment surface, and a brace comprising a member slanting in a plane substantially parallel to that of the abutment surface
25 when the lid is in a determinate open position, and adapted to engage with said surface, and means co-operating with the member to lock it in its adjusted position by the weight of the lid.
